CLAIM

The ornamental design for a garlic press, as shown and described.

DESCRIPTION

FIG. 1 is a top, front, right-side, perspective view of a garlic press;

FIG. 2 is a bottom, rear, left-side, perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a top, front, right-side perspective view of the garlic press shown in an open position;

FIG. 10 is a bottom, rear, left-side, perspective view thereof shown at a reduced scale;

FIG. 11 is a front elevation view thereof;

FIG. 12 is a rear elevation view thereof;

FIG. 13 is a left-side elevation view thereof;

FIG. 14 is a right-side elevation view thereof;

FIG. 15 is a top plan view thereof shown at a reduced scale; and,

FIG. 16 is a bottom plan view thereof shown at a reduced scale.

In the drawings, the broken lines are for the purpose of illustrating portions of the garlic press and form no part of the claimed design.

1 Claim, 12 Drawing Sheets
